US0D1058818S

(12) **United States Design Patent** (10) Patent No.: **US D1,058,818 S**
(45) Date of Patent: ** Jan. 21, 2025

(54) **BIOMEDICAL DEVICE SUPPORT**

(71) Applicant: **EUROSETS S.r.l.**, Medolla (IT)

(72) Inventors: **Antonio Petralia**, Medolla (IT); **Paolo Fontanili**, Medolla (IT); **Alessandro Zerbini**, Medolla (IT)

(73) Assignee: **EUROSETS S.R.L.**, Medolla (IT)

(**) Term: **15 Years**

(21) Appl. No.: **35/516,259**

(22) Filed: **Feb. 17, 2022**

(80) **Hague Agreement Data**

Int. Filing Date: **Feb. 17, 2022**

Int. Reg. No.: **DM/220304**

Int. Reg. Date: **Feb. 17, 2022**

Int. Reg. Pub. Date: **Feb. 17, 2023**

(51) **LOC (15) Cl.** 24-02

(52) **U.S. Cl.**

USPC **D24/186**

(58) **Field of Classification Search**

USPC D24/216, 186, 232, 111, 219, 234;

D10/81

CPC A61M 1/3666; A61M 1/3639; A61B 90/50

See application file for complete search history.

(57) **CLAIM**

The ornamental design for a biomedical device support, as shown and described.

DESCRIPTION

1.1 is a top perspective view;

1.2 is a top view;

1.3 is a bottom view;

1.4 is a front view;

1.5 is a rear view;

1.6 is a side view; and

1.7 is a side view.

The features shown in broken lines are for the purpose of illustrating portions of the biomedical device support that form no part of the claimed design.
